UNITED STATES PATENT OFFICE.

JOHN GORDON SUMMERS, OF SAN DIEGO, CALIFORNIA.

TURBINE.

Application filed January 26, 1921. Serial No. 440,065.

To all whom it may concern:

Be it known that I, JOHN GORDON SUMMERS, a citizen of the United States, residing at San Diego, in the county of San Diego and State of California, have invented a new and useful Turbine, of which the following is a specification.

This invention relates to a turbine, one of its objects being to provide a simple structure of this character adapted to be operated by steam, air or gas, there being simple and efficient means whereby the flow of pressure into the stator can be so controlled as to drive the rotor either clockwise or counter-clockwise as desired.

A still further object is to provide a rotor having a novel form of sinuous impact receiving channel provided with regularly spaced cut-offs whereby, during the actuation of the rotor, intermittent impulses are transmitted thereto from nozzles discharging into the stator.

A further object is to provide a structure of this character in which are provided sealing rings or washers readily adjustable and which engage opposed faces of the rotor, thus to prevent leakage between the rotor and the walls of the stator.

With the foregoing and other objects in view which will appear as the description proceeds, the invention resides in the combination and arrangement of parts and in the details of construction hereinafter described and claimed, it being understood that, within the scope of what is claimed changes in the precise embodiment of the invention shown can be made without departing from the spirit of the invention.

In the accompanying drawings the preferred form of the invention has been shown.

In said drawings

Figure 1 is a view partly in elevation and partly in section of a turbine embodying the present improvements.

Figure 2 is a section on line 2—2, Figure 1.

Figure 3 is a plan view of a motor including a high pressure and a low pressure turbine, the connections between the two stators being illustrated.

Figure 4 is an enlarged section through a portion of the stator and showing the adjustable yieldingly pressed sealing ring.

Referring to the figures by characters of reference 1 designates the base of a cylindrical stator 2 one head 3 of which can be made

integral with the circumferential portion of the stator if preferred and is provided, at its margin, with an annular groove or channel 3'. The other head 4 of the stator is preferably removable, it being detachably connected to the marginal portion of the stator by bolts 5 or the like. This removable head has an annular groove or channel 6 arranged oppositely to and corresponding with the channel 3' and in both channels are movably mounted sealing rings 7 preferably split as shown at 8 and these rings are provided with backings consisting of leaf springs 9 in which are swiveled adjusting screws 10. These screws extend through the outer walls of the channels 3' and 6 and by means thereof the tension of the springs 9 can be varied so that the springs will press against the rings 7 with any desired degree of pressure. Each of the screws 10 can be provided with a lock nut as indicated at 11.

Formed on the inner surface of the periphery of the stator, preferably adjacent the top thereof, are spaced pairs of ribs or projections 12 having tapered openings 13 therein in communication with threaded bores 14 extending through the wall of the stator. In each of these bores is arranged a threaded nozzle 15 having a tapered discharge end seated within the tapered portions 13 and each nozzle has a head 16 whereby it can be rotated so as to be adjusted longitudinally within the bore 14. A pressure supply pipe 17 opens into each of the nozzles. The nozzles 15 of each pair are inclined oppositely to the nozzles of the other pair and the nozzles of each pair are tangentially disposed relative to an imaginary circle within the stator. Extending across the ribs 12 of each pair is a cut off plate 18 having openings 19 registering with the outlet ends of the bores 14, each of these plates bridging the spaces between the ribs of the engaged pair and the ends of the plates being offset outwardly and secured to the wall of the stator as shown at 20.

Arranged within the wall of the stator and between the uppermost nozzles of the two pairs is an outlet port 21 in communication with an outlet pipe 22.

Journalized within the middle portions of the heads 3 and 4 is a shaft 23 to which is keyed or otherwise secured a rotor 24 arranged within the stator and fitting snugly against the two heads. The peripheral portion of this rotor is spaced from the wall

of the stator as shown particularly in Figure 1 but is adapted to work upon the inner faces of the cut off plates 18. The rings 7 are pressed against the sides of the rotor at its periphery and serve to seal the sides of the spaces between the rotor and the stator. This is clearly shown in Figure 2.

The rotor is provided in its periphery with a continuous sinuous groove or channel 25 and at regular intervals this channel or groove is bridged by cut off plates 26 the outer surfaces of which are flush with the periphery of the rotor. The plates are so proportioned that the distance between the advancing edge of each plate and the opposed edge thereof is slightly less than the distance between the two outlets 19 of each plate 18. Thus it will be seen that during the operation of the rotor each cut off plate 26 will extend across one of the outlets 19 of a pair while the other outlet 19 is open but as the cut off plate passes across the second outlet port 19 the first one will become exposed. Thus the pressure is delivered alternately through the two outlets 19 of the active pair and caused to be projected intermittently in jets into the sinuous groove 25 so that the rotor is given intermittent impulses and caused to rotate at a high speed.

The flow of steam, gas or other like propelling medium to the various nozzles is controlled by valves as indicated at 27 in Figure 3.

Obviously by closing one of the valves 27 the motive fluid will be directed solely to the set of ports controlled by the other valve and when delivered through the nozzles which are thus left in communication with the source of pressure the jets of steam, gas or the like will be directed intermittently as heretofore described and cause the rotor to operate in one direction. By operating the valves so as to direct the pressure to the other pair of nozzles, the operation of the rotor will be reversed, as will be obvious.

If desired two turbines can be combined as shown in Figure 3 so as to provide a high pressure turbine A and a low pressure turbine B, the exhaust pipe 22 extending from the high pressure turbine to the branch pipes 28 leading to the delivery nozzles of the low pressure turbine.

What is claimed is:

55. 1. The combination with a stator having two pairs of nozzles discharging thereinto, the nozzles of one pair extending in one direction and those of the other pair in the

opposite direction, said nozzles being tangential to an imaginary circle concentric with the stator, the inner face of the periphery of the stator being provided with spaced pairs of ribs having tapered openings therein, said stator having threaded bores extending through the walls thereof and communicating with said openings, a nozzle arranged in each bore, a rotor arranged within the stator and having a continuous sinuous channel in its periphery and cooperating means carried by the stator and the rotor whereby the operating fluid is delivered alternately through the nozzles of the active pair and caused to be projected intermittently in jets into the sinuous groove of the rotor, thereby imparting intermittent impulses to the rotor and causing it to rotate at high speed in its perimeter.

2. The combination of a stator including heads and having an annular channel at its margin on its inner face, spring seated sealing rings closing said channels, spaced pairs of ribs on the inner face of the periphery of the stator, said ribs having tapered openings, those of one pair of ribs extending in a direction opposite to those in the other pair, the wall of the stator having threaded bores communicating with said openings, nozzles mounted in said bores and openings, the nozzles of each pair being tangentially disposed relative to an imaginary circle within the stator, a cut off plate extending across the ribs of each pair and having openings registering with the nozzle openings, said plate spanning the space between the ribs of each pair and having their ends offset outwardly and secured to the wall of the stator, an outlet arranged between the two pairs of nozzles, a rotor spaced peripherally from the stator and working on the cut off plates thereof, the rotor having a sinuous channel in its periphery, cut off plates bridging said channel in its periphery, cut off plates bridging said channel at regular intervals and of a length slightly less than the distance between the outlets in the cut off plates of the stator, whereby intermittent impulses are imparted to the rotor by the alternate delivery of the actuating fluid through the active pair of nozzles.

In testimony that I claim the foregoing as my own, I have hereto affixed my signature in the presence of two witnesses.

JOHN GORDON SUMMERS.

Witnesses:

REUBEN ENOCH SUMMERS,
GEO. W. BOWLER.
